MOUNTING DEVICE FOR DOOR CLOSERS

Kenneth C. Hoernel, Racine, Wis.

Application April 20, 1948, Serial No. 22,050

7 Claims. (Cl. 248—200)

1

The present invention relates to door closers and devices for mounting the same, and an object of the invention is to generally improve the construction and operation of devices of this class. A door closer of the type contemplated usually comprises a spring for closing the door and a fluid chamber or dash-pot with the necessary links and connections so that the spring tends to close the door at all times while the dash pot limits the rate of closing so as to avoid slamming of the door with accompanying noise and danger of injury to persons or structure. Such devices are well-known and made in various styles and sizes, and they are commonly installed on the movable parts of the doors. Each has a link extended to a stationary part of the door frame as a thrust point against which the closer exerts the necessary force to propel itself and the door to closed position. Such closers are commonly provided with vertical pads of sizes proportioned to each particular closer, and having the necessary holes so that it can be fastened to the door with screws or the like for a substantial mounting. This arrangement is objectionable when used on an outwardly swinging outside door for the reason that the entire mechanism is carried outside with the door and exposed to the elements to a much greater extent that it would be if it could be located within the building and the link connection extended to the door so that only the link would be so exposed. However, up to the time of the present invention, the large variety of styles and sizes of door closers presently available made it impractical to supply fittings for this type of installation, which was needed only occasionally since, lacking metal working equipment at the site of installation, it was necessary to carry in stock a large number of sizes as well as styles of brackets in order to fit the various sizes of door closers. Using the device of the present invention it is necessary to carry only one size and perhaps four styles in order to fit substantially any installation.

Accordingly it is a further object of the invention to provide an installation member or bracket for a door closer which will enable a door closer to be installed within the building where it is used, and which will fit a great number of sizes and styles of door closers without alteration.

Further objects and advantages will become apparent from the following description and accompanying drawings in which satisfactory embodiments of the invention are shown, but it is to be understood that the invention is not intended to be taken as limited to the precise con-

2

struction disclosed, or in fact in any manner except as defined in the claims. In the drawings

Figure 1 is an elevation of the device of the invention in place in a door-way, the door frame and a typical closer installed thereon being designated in broken lines.

Fig. 2 is a similar view of a modified form of the device for installation on the soffit further from the corner of the door frame.

Fig. 3 is a similar view of a further modified form of the device for installation substantially flush with the inner surface of the door frame or building wall.

Fig. 4 is a similar view of a further modified form for installation within a curved-top door frame.

Turning to Fig. 1, a device illustrative of the invention comprises an attaching portion generally designated as 5 having flanges 6 and 7 for attachment to a door frame 8, the flanges providing holes for screws 9—9 for attaching the device firmly in the corner of the door frame. A web 10 extends generally downwardly away from flanges 6 and 7 and forms a portion connecting them with a pad 11, ribs 12 and 13 being preferably formed on the edges of the web to give it additional strength and stiffness. Pad 11 is preferably substantially rectangular, and of a size to receive the attaching flange 14 of the largest size door closer 15 which the device is intended to accommodate.

Pad 11 is pierced with a plurality of holes, in the present instance four, designated as 16, 17, 18 and 19, and which are elongated or slotted and inclined from the corners of pad 11 toward the center thereof. Fastening devices such for example as bolts 20, 21, 22 and 23 are received in holes 16, 17, 18 and 19 respectively, and the holes are of such a size as to allow some freedom of the bolts therein, and the holes are inclined somewhat more than enough to extend toward the center of the pad, and in fact preferably extend along a line which passes somewhat to the side of the center opposite the side nearest that particular hole. In other words, if the diagonals of the rectangular pad were laid out, the holes would be inclined somewhat too much to lie on said diagonals, but the two holes at either end of the pad, that is adjacent proximal corners of the pad, if extended would meet at a point short of the intersection of the diagonals, or on the side thereof nearest the holes.

A pad of the type described, it is found, will provide for mounting the majority of all door closers currently manufactured, the idiosyncrasies

of the various makes and models requiring attaching fastenings which, regardless of size of closer, will pass through holes 16, 17, 18 and 19 without binding or alteration of the closer or bracket pad. Web 10 may have an opening 24, if desired to avoid unnecessary weight, and an additional rib 25 adds further to the stiffness and stability of the device.

Fig. 2 shows a structure of generally similar type, there being a flange 26 providing openings 34, 35 and 36, through which are received fastenings 37, 38, 39 and 40, for mounting thereon the pad 41 of a door closer, in this instance of a comparatively small size. The position of the fasteners 37, 38, 39 and 40 is illustrative of one extreme adaptation of the device to a small closer, while the position shown in Fig. 1 of fastenings 20, 21, 22 and 23 is illustrative of the other extreme adaptation of the device to a large closer. In either arrangement the closer mechanism is supported on the device, instead of on the door, and a linkage generally designated as 42, Fig. 1, extends to and is fastened to the movable part of the door.

Fig. 3 shows a structure for use where there is insufficient room on the soffit for application of the device of the type of Figs. 1 or 2. In this arrangement there is a relatively large pad or flange 43 which, unlike the embodiments of the previous figures lies in the plane of the inner wall of the building. It provides openings 44—44 which are for the purpose of receiving screws or similar fastenings, not shown, for attaching the device to the inner surface of the building wall. A web portion 45 having ribs 46 and 47 extends downwardly from flange 43 and connects with a pad 48 having openings 49, 50, 51 and 52 essentially similar in position and function to openings 33, 34, 35 and 36 of Fig. 2. Pads 48, 11 and 32 may be reinforced if desired with additional ribs 53, 54, and 55.

A further modification is shown in Fig. 4 in which an attaching flange 56 is curved in a manner to fit within the arched portion of a curved door frame 57. Flange 56 is provided with openings for screws 58—58 for solidly attaching it to the frame and has a downwardly extending arm 59 integrally or rigidly attached thereto. Arm 59 has a clamping device 60 of any suitable or well-known type pivotally securing thereto a pad 61 provided with openings 62, 63, 64 and 65 for receiving the fastening devices of a door closer in the manner described in connection with Figs. 1 and 2. In applying this device, flange 56 is attached to the door frame in the most advantageous position after which, with clamping device 60 loose, pad 61 is swung thereabout until it is in position to support a closer in proper position—commonly with its longer sides horizontal—clamping device 60 being then tightened so as to maintain the parts in adjusted position. If desired flange 56 may be formed with a curve which increases toward the openings for screws 58—58, whereupon it will have a firm bearing on door frames of a variety of different curvatures.

The operation of the various embodiments of the invention is thought to be clear from the foregoing description, it being apparent that door closers of various sizes and styles can be readily mounted on the devices, and when so mounted will be firmly supported within the building, and

will not swing outside so as to be damaged by the weather, when the door is opened.

The above being a full and exact description of devices embodying the invention, what is claimed as new and desired to be secured by Letters Patent of the United States is:

1. In a device of the class described a door frame engaging flange portion having means for permanent attachment to a door frame, a connecting web portion forming a supporting arm, extending from said flange portion, and a closer attaching pad carried by said connecting web portion, said pad providing opposed laterally spaced pairs of slotted attaching fastening receiving holes, the holes of each pair being inclined inwardly toward each other from the outer margins of said pad at greater angles than the diagonals of the rectangle defined by the outer margins of said holes each pair of holes extending toward a point of intersection spaced in the direction of said pair of holes from such point of intersection of the other holes for receiving fastenings from any one of a variety of sizes and styles of door closers.

2. In a bracket for a door closer to be mounted on a door frame the combination of a flange portion, means for attaching said flange portion within the confines of the door frame, a closer attaching pad of substantially rectangular proportions, a connecting web uniting said flange portion with said attaching pad, said pad providing opposed laterally spaced pairs of fastener receiving holes in which are received fasteners attaching a door closer to said pad, and said holes being slotted, and the holes of each pair being inclined inwardly from the outer margins of said pad toward each other and the middle of the pad at greater angles than the diagonals of the rectangle defined by the outer margins of said holes each pair of holes extending toward a point of intersection spaced in the direction of said pair of holes from such point of intersection of the other holes so as to be capable of receiving fasteners engaged with any one of a plurality of different sizes of door closers.

3. In a bracket for a door closer to be mounted on a door frame the combination of a flange portion, means for attaching said flange portion within the confines of the door frame, a closer attaching pad of substantially rectangular proportions, a connecting web uniting said flange portion with said attaching pad, said pad providing four fastener receiving holes in which are engaged fasteners attaching a door closer to said pad, said holes being slotted and inclined inwardly from adjacent the proximal corners of said pad said holes being inclined toward each other at angles greater than the diagonals of the pad each pair of holes extending toward a point of intersection spaced in the direction of said pair of holes from such point of intersection of the other holes toward the middle of the pad so as to receive the fasteners engaged with any one of a plurality of sizes of door closers.

4. In a bracket for a door closer to be mounted on a door frame the combination of an angular flange portion for engagement with an upper and a side surface of a door frame, means for attaching said flange portion to said surface, a closer attaching pad of substantially rectangular proportions, a connecting web uniting said angular flange portion with said attaching pad, said pad providing four fastener receiving holes in which are engaged fasteners attaching a door closer to said pad, said holes being slotted and inclined

inwardly from adjacent the proximal corners of said pad said holes being inclined toward each other at angles greater than the diagonals of the pad each pair of holes extending toward a point of intersection spaced in the direction of said pair of holes from such point of intersection of the other holes toward the middle of the pad so as to receive the fasteners engaged with any one of a plurality of different sizes of door closers.

5. In a bracket for a door closer to be mounted on a door frame the combination of a pad portion for engagement with an outer surface of a door frame, means for attaching said pad portion to said outer surface, a closer attaching pad of substantially rectangular proportions, a connecting web uniting said pad portion to said attaching pad, said pad providing four fastener receiving holes in which are engaged fasteners attaching a door closer to said pad, said holes being slotted and inclined inwardly from adjacent the proximal corners of said pad toward the middle of the pad said holes being inclined toward each other at angles greater than the diagonals of the pad each pair of holes extending toward a point of intersection spaced in the direction of said pair of holes from such point of intersection of the other holes so as to receive the fasteners engaged with any one of a plurality of different sizes of door closers.

6. In a bracket for a door closer to be mounted on a door frame the combination of an attaching portion for engagement with a portion of a door frame, means for fastening said attaching portion to said door frame, a closer attaching pad of substantially rectangular proportions, a clamping device pivotally connecting said attaching portion with said closer attaching pad, means on said clamping device for rigidly fixing said attaching portion and said closer attaching pad in relatively adjusted positions, said pad providing four fastener receiving holes in which are engaged fasteners attaching a door closer to said pad, said holes being slotted and inclined inwardly from

adjacent the proximal corners of said pad toward the middle of the pad said holes being inclined toward each other at angles greater than the diagonals of the pad each pair of holes extending toward a point of intersection spaced in the direction of said pair of holes from such point of intersection of the other holes so as to receive the fasteners engaged with any one of a plurality of different sizes of door closers.

5 7. In a device of the class described a door frame engaging flange portion having means for permanent attachment to a door frame, a connecting web portion forming a supporting arm, extending from said flange portion, and a closer attaching pad carried by said connecting web portion, said pad providing opposed laterally spaced pairs of slotted attaching fastening receiving holes, the holes of each pair being inclined toward each other from the outer margins of said pad, each toward a point of intersection spaced in the direction of the holes, from such point of intersection of the other holes.
